US0D1101581S

(12) **United States Design Patent** (10) **Patent No.:** **US D1,101,581 S**
(45) **Date of Patent:** **** Nov. 11, 2025**

(54) **SET OF BANDS FOR WRIST WORN DEVICE**

(71) Applicant: **Fitbit, Inc.**, San Francisco, CA (US)

(72) Inventors: **Brian Dennis Paschke**, San Francisco, CA (US); **Anthony Gerald Kern**, Pleasant Hill, CA (US); **Yidan Zhang**, Emeryville, CA (US); **Jonah Avram Becker**, San Francisco, CA (US); **Benjamin Patrick Robert Jean Riot**, San Francisco, CA (US); **Bobin Gao**, San Francisco, CA (US); **Eric John Fairbanks**, Lafayette, CA (US); **Junyong Park**, San Francisco, CA (US)

(73) Assignee: **Fitbit, Inc.**, San Francisco, CA (US)

(**) Term: **15 Years**

(21) Appl. No.: **29/776,315**

(22) Filed: **Mar. 29, 2021**

Related U.S. Application Data

(62) Division of application No. 29/745,539, filed on Aug. 6, 2020, now Pat. No. Des. 929,879.

CLAIM

The ornamental design for a set of bands for wrist worn device as shown and described.

DESCRIPTION

FIG. 1 is a top, right side isometric view our new design for a set of bands for wrist worn device.

FIG. 2 is a top plan view thereof.

FIG. 3 is a bottom plan view thereof.

FIG. 4 is a left side elevation view thereof.

FIG. 5 is a right side elevation view thereof.

FIG. 6 is a front side elevation view thereof; and,

FIG. 7 is a back side elevation view thereof.

The features shown in broken lines represent portions of the set of bands for wrist worn device and form no part of the claimed design.

1 Claim, 5 Drawing Sheets
